MACHINE FOR PLAYING BRIDGE

John J. Hickey, Arlington, N. J.

Application June 10, 1942, Serial No. 446,426

9 Claims. (Cl. 273—148)

This invention relates to machines for playing games and refers more particularly to a machine for playing auction or contract bridge and similar games which are usually played with a deck of 52 or 53 playing cards.

An object of the present invention is the provision of a game playing machine which can be conveniently used by crippled or aged persons or persons afflicted with various nervous ailments, who are unable to hold, shuffle or deal playing cards, for the purpose of playing various games, such as bridge or whist, similar to those which are played by means of cards.

Another object is the provision of a novel and entertaining substitute for card games, consisting of a machine the operations of which replace various manipulations which must be carried out in the course of bridge, whist and other card games.

A further object is to substitute playing cards by units which are not affected by gusts of ordinary winds, thus making it possible to play card games, such as bridge, outdoors, for instance, on lawns, beaches and decks of moving steamships.

A still further object is to eliminate the slow manual shuffling and dealing of playing cards which afford undue advantages to players with long practice, and to substitute therefor a more rapid, efficient and uniform machine-shuffling and machine dealing of playing units.

Still another object is to provide an entertaining departure in card games which is more suitable for the head table at bridge parties.

Other objects of the present invention will become apparent in the course of the following specification.

In accomplishing the objects of the present invention it was found desirable to provide a bridge-playing machine comprising a wheel wherein the mixing of balls or other rotary elements serving as a substitute for cards takes place. The balls are introduced by the wheel into a counting device which supplies the correct number of balls to the places occupied by players in the course of the game, these places being provided with suitable means for holding the balls which are concealed from other players, for sorting the balls, for playing them singly and for transferring the dummy hand to its playing position. Balls may be transmitted to playing location and taken as tricks, means being provided to record tricks and the bidding. The dummy hand may be conveniently raised and made visible to the players. The

playing location is connected with means returning the balls back to the mixing wheel.

The invention will appear more clearly from the following detailed description when taken in connection with the accompanying drawings showing, by way of example, a preferred embodiment of the inventive idea.

In the drawings:

Figure 1 is a perspective view of the top of a bridge playing table or machine constructed in accordance with the principles of the present invention.

Figure 2 is a top plan view with some parts shown in section.

Figure 3 shows the mixing wheel and is a section along the line 3—3 of Figure 4.

Figure 4 is a section along the line 4—4 of Figure 3.

Figure 5 is a section along the line 5—5 of Figure 2.

Figure 6 is a section along the line 6—6 of Figure 5.

Figure 6a is a perspective view of a tray-actuating device.

Figure 7 is a section along the line 7—7 of Figure 2.

Figure 8 is a perspective view of the ball-counting device.

Figure 9 is a perspective view of two trays in dealing and playing positions.

Figure 9a shows the two trays in the sorting position.

Figure 9b shows the two trays in the return position.

The machine shown in the drawings is used to play games similar to those played by means of cards. Playing cards are substituted by balls 29 which may be made of wood, ordinary or magnifying glass, porcelain, plastics, ivory, cement or any other suitable material. The balls may be made in convenient sizes ranging from three-quarters of an inch to one and one-half inches in diameter and may be of four colors which are a well recognized component of ordinary playing cards, namely, black for spades, blue for clubs, red for hearts and white or ivory for diamonds. The balls are numbered, lettered and decorated in a manner similar to that provided on playing cards, possibly, with the addition of luminous markings and the effects of magnifying glass.

The drawings illustrate a machine for playing auction or contract bridge, sometimes referred to as whist. The machine constitutes the top 21 of a table which may be made of

wood and metal parts, although satisfactory tables may be made wholly, or in combination, of metal, plastics or other suitable materials. The table may be round, octagonal or of any other shape to suit different requirements.

The table top 21 shown in Figures 1 and 2 is approximately thirty-two inches square and is supported by legs 22. The table has positions for four players, the places for the players being designated by numerals 1 to 4. The customary card dealer is replaced by an operator and the players in the first and fourth locations are in positions enabling them to operate the machine most conveniently.

The machine includes a plurality of inclined surfaces, so as to enable the balls 20 to roll by gravity throughout the machine from their highest location upon a transmitting platform 26 (Fig. 3) to a hopper or channel 25 which is inclined toward a mixing wheel 23.

The mixing wheel 23 comprises a casing 24 which is open on the side directed toward the table top 21 so that the interior of the wheel is always in communication with the ball receiving channel 25 and the ball transmitting platform 26. The casing 24 is rotatable along with its shaft 27 which is mounted in a support 28 enclosing the wheel and connected to the table top, and is also mounted in a wall 29 constituting a part of the table top. A handle 30 is used to rotate the shaft 27 and the casing 24 connected therewith.

The rim of the casing 24 carries a plurality of baffles 31 each of which has a straight wall 32 and a hook-shaped element 33 provided with a surface 34 which is inclined in the direction toward the table.

The wheel 23 may be rotated in opposite directions and may contain a substantial number of balls 20. When the wheel is rotated in one direction, the baffles 31 will lift the balls, which rest in the casing, various heights up to six inches and project them on top of the mass of balls in the channel and will rotate the whole mass thus mixing them thoroughly. When the wheel is rotated in the opposite direction, the hook-shaped portions 33 of the baffles 31 will entrap some of the balls and raise them while continuing to mix the mass of balls. Due to the inclination of the surfaces 34 upon which the balls rest, the balls will roll conveniently upon the inclined platform 26 and will be dealt to the players by a counting and distributing device 35, shown in Figures 2 and 8.

The trays and tubes constituting a part of the distributing device are situated within a rectangular casing 36 enclosing an inner space 37.

A partition wall 38 extends between the platform 26 and a corner formed by two inner walls 39 and 40. Two short walls 41 and 42 extend parallel to the wall 38.

A door 43 may separate the platform 26 from the space between the walls 38, 41 and 42. The door 43 carries a pin 44 extending through the top 45 of the casing and provided with a knob 46. Two rods 47 and 48 have ends which are attached to the door 43. The rods are pivoted intermediate their ends at 49 and 50 and extend parallel to the walls 39 and 40, respectively. An inclined rail 51, which is U-shaped in cross section (Fig. 5), has a wall 52 connected to the wall 39 and a parallel wall 53. A groove or channel 54 is formed between the rod 47 and the walls 39 and 52. Another groove or channel

55 is provided between the rod 47 and the wall 53. The rod 47 carries a pin 56 extending into the channel 54 and another pin 57 extending into the channel 55.

5 A similar inclined rail is connected to the wall 40 and is divided by the rod 48 into two grooves or channels 58 and 59. The rod 48 carries pins (not shown) similar to the pins 56 and 57 and projecting into channels 58 and 59.

10 When the door 43 is raised, the balls 20 will roll from the platform 26 and into the channels 54, 55, 58 and 59 until they are stopped by the pins carried by the rods 47 and 48. The door 43 may be held in its raised position by frictional engagement of the pin 44, or by any other suitable means not shown in the drawings.

When playing the game of bridge, the balls 20 may be one inch in diameter and the length of each of the channels 54, 55, 58 and 59 between its pin and the door 43 may be equal to thirteen inches, so that thirteen balls will be located in each channel, this being the number required for each playing hand of bridge.

The position of the pins upon the rods 47 and 48 may be varied to enable the channels to hold ten, twelve or any other desired number of balls and thereby utilize the machine for playing games other than bridge, such as pinochle, pedro and other games. For the kitty's pockets may be added to the device.

The channel 55 is in communication with a curved channel 60 leading to an outer tray 61 constituting a part of a sorting and playing device 62. The device 62 is situated within the table below its top and is visible through a window 63 only to the player who is using it, while it is completely invisible from the locations of the three other players provided with similar devices (Fig. 1).

40 The outer tray 61 extends parallel to an inner tray 64 and ends at a wall 98 (Fig. 6) situated below the channel 60. Both trays are pivoted at 65 close to their left hand ends (looking in the direction of Figure 6) and are separate from each other by edges 66 and 67 which, however, do not extend to the left hand ends of the tray (Fig. 9).

Balls are held upon the trays by a line of brush 70 and a barrier 71 constituting a bent edge of a bar 72. The bristles 70 are carried by an elongated bar 73 suspended by brackets 74. The line of brush 70 consisting of animal hair may be conveniently substituted by rubber prongs or similar yielding or elastic material. The purpose of the line of brush 70 is to hold the balls securely in line and also to permit a player to select any one of the balls 20 and by slight pressure of his thumb or fingers, press it through the line of brush 70 from the outer tray 61 and into the inner tray 64. This is particularly helpful to a crippled or impaired player in that he is completely relieved of the burden of holding up his playing hand throughout the long round of play and his sorting and playing activities are reduced to the minimum in effort.

61 The bar 72 is pivoted at 91 and carries a downwardly extending bracket 75 provided with a pivot 76 carrying a bearing 77 for a roller or wheel 78.

The trays 61 and 64 carry downwardly extending cams 79 and 80, respectively, which are provided with surfaces slanting in opposite directions (Fig. 6).

The roller 78 and the cams 79 and 80 may be engaged by various portions of a cam plate 81 which is connected by a plate 82 with a sleeve 83. The sleeve 83 is situated below the table top

(Fig. 1) and is mounted upon a rod 84 which is suspended from the table top by brackets 85. The cam plate 81 comprises a flat surface 86 upon which the roller 78 and the cams 79 and 80 may rest (Fig. 6a). The plate 81 also carries an upwardly projecting piece 87 upon which the roller 78 may ride. The cam 79 of the outer tray 61 may ride upon a downwardly inclined surface 88. The cam 80 of the inner tray 64 may ride upon an upwardly extending projection 89 and a downwardly inclined surface 90.

The cam carrying plate 81 may be operated to shift the trays 61 and 64 into three positions indicated in Figures 9, 9a and 9b. The sorting of the balls is carried out while the trays are in the position shown in Figure 9a, by pushing the balls singly from the outer tray 61 to the inner tray 64. Balls collected in the inner tray 64 are returned to the outer tray 61 in the desired order by operating the plate 81 to shift the trays to the position shown in Figure 9b.

Balls are played singly by being pushed from the outer tray 61 to the inner tray 64 while the trays are in the position shown in Figures 6 and 9; in this position the two trays are slightly inclined downwardly in the direction toward the barrier 71 of the bar 72. The adjacent end of the inner tray 64 is in communication with a channel 92 which leads to the playing channel 93 (Figs. 2 and 7). A channel 94 connects the adjacent end of the outer tray 61 with the playing channel 93. A door 95 is situated between the tray 61 and the channel 94 and may be raised by lifting a handle 96 which extends through a slot 97 provided in the table casing (Fig. 1). The door 95 is raised when playing the dummy hand.

The playing channel 93 extends diagonally across the inner space 37 of the machine and is located at the bottom thereof. The channel 93 has two end portions which are inclined downwardly toward a central portion (Fig. 1), while the floor of the central portion is inclined toward an opening 99 communicating with the return channel 25 (Fig. 7). The opening 99 is usually closed by a flange 100 of a lever 101 which is pivoted at 102 (Fig. 2) and is connected by a rod 103 with another lever 104. The lever 104 is pivoted at 105. The levers 101 and 104 are maintained in place by a spring 106.

Two chains or wires 107 are connected to the lever 101 and lead to locations of two different players. Two other wires 107 are connected to the lever 104 and lead to the locations of the other two players. The ends of the wires 107 carry rings 108.

Each wire 107 operates a separate counting device 109 which includes a lever 110 pivoted at 111 and connected with the wire. The lever 110 carries a pawl 112 meshing with a gear wheel 113 which is connected with a pointer or hand 114 moving over a scale 115.

A channel 116 for the dummy hand may be inserted into the playing channel 93, or may be raised above the channel 93 by a lever 117 (Fig. 7) which is pivoted at 118 and which is connected at 120 to a vertical rod 119 connected to the channel 116. The rod 119 passes through the floor 121 of the inner space 37 of the machine.

The playing of the game begins by inserting all the balls 20 representing a deck of cards, into the channel 25. The balls roll down the inclined surfaces of the channel 25 and assemble in the lower part of the mixing wheel 23 and the adjacent part of the channel 25. The mass of balls is stirred and mixed in the described manner by rotating

the wheel 23 in the direction of the arrow provided with the word "mix" in Figure 4.

Then the dealing of the balls is accomplished by rotating the wheel 23 in the opposite direction. 5 The baffles 33 will lift all of the balls 20 after a few revolutions of the wheel 23. The balls will roll down the inclined surfaces 34 of the baffles 33 and upon the platform 26.

As the game proceeds, the wheel 23 will repeatedly restore the balls to their higher elevation 10 and will enable a rolling of the balls to the appropriate locations in the machine.

If the door 43 is raised, the balls will roll in the channels 54, 55, 58 and 59 until they are 15 stopped by the pins carried by the rods 47 and 48. When the dealing knob 46 is pressed downwardly, the rods 47 and 48 will turn and raise their pins, thereby permitting the correct number of balls to roll down the channels and into the 20 four outer playing trays 61. At this time, the outer trays 61 and the inner trays 64 are in the position shown in Figures 6 and 9.

Each player now proceeds to sort his hand. For 25 this purpose, the player shifts his sleeve 83 to the position marked "sort" in Figure 1. The plate 81 and the cams carried thereby move along with the sleeve 83. The projection 87 will be withdrawn from engagement with the roller 78 which will be placed upon the surface 86 (Fig. 6a). 30 Then the bar 72 will be turned downwardly upon its pivot 91 and the barrier 73 will be placed between an end of the tray and the channel 92. At the same time, the cam 80 of the inner tray 64 will follow the inclined surface 90 and the tray 64 will be inclined downwardly, with the free end of the tray facing a wall 98 of the casing. This 35 position is shown in Figure 9a.

Then the player sorts his hand by pressing the balls singly through the brush 70 from the outer tray 61 to the inner tray 64 and thereby assembling the spades in one group and likewise the clubs, diamonds and hearts; each suit can thereby also be sorted in the sequential order desired by the player. The balls are assembled in the inner tray 64 at the lower end of the tray close to the wall 98.

After completing the sorting, a player shifts the sleeve 84 to the position designated as "return" 50 in Figure 1. In this position, the roller 78 is again upon the surface 86 of the plate 81 (Fig. 6a), so that the barrier 71 of the bar 72 remaining between the tray 64 and the channel 92; however, the tray 64 is now swung outwardly by the projection 89 which engages the cam 80 of the tray 64. On the other hand, the outer tray 61 is 55 downwardly inclined, since its cam 79 rides upon the inclined surface 88 of the plate 81. This position is illustrated in Figure 9b. Then the sorted balls will roll by gravity down the tray 64 and will be deflected upon the tray 61 at the barrier 71, whereupon the balls roll upon the tray 61 to its end.

After the sorting of the hands, the players bid for the trump in the same manner in which the bidding is conducted when playing cards are used. 60

Following the bidding, any one of the four 65 players may transfer the dummy hand, from an outer tray 61 by raising the knob 96 and the door or sluice-way 95 (Fig. 1). At that time the channel 116 for the dummy hand is located within the playing channel 93. The balls will roll down the tray 61 and the channel 94 (Fig. 2) and into the channel 116. Then a player turns the lever 117 and raises the channel 116 above the playing 70 channel 93, as indicated in Figures 1 and 7, so

that the dummy hand is visible to all four players.

Each of these three hands remaining in the outer trays 61 can be played in the regular sequential manner, one ball at a time, by pressing each ball through the brush 70 into the inner tray 64 from which the balls will roll by gravity through the channel 92 and into the playing channel 93.

The pushing of the balls singly from an outer tray 61 to the inner tray 64 is a simple movement particularly suited for crippled or impaired persons. Such players are relieved of the burden of holding up hands of cards and of the two-headed action in sorting the hands of cards.

The dummy hand can be played one ball at a time, by the action of any of the players in lifting the balls singly by hand from the raised channel 116 and depositing them in the playing channel 93.

Each round of play will accumulate four balls in the playing channel 93, from which the players determine which of them has won and can take the trick in the same manner in which such decision arises when playing cards are used. The player winning the trick pulls his ring 108 and chain or wire 107, thereby actuating the lever 101 which frees the opening 99 and thus sends the four balls by gravity to the hopper or channel 25 and the wheel 23. The trick is recorded by the counting device 109 which moves forward the pointer 114.

It is apparent from the above that balls are visible to all the players when they are located in the channels 93 and 116, that balls in each sorting device 62 are visible only to one player and that at all other stages of the operation of the machine the balls are contained in enclosed parts and are not visible to the players or contestants.

It is apparent that the machine shown above is given by way of illustration and not by way of limitation and that the above described illustration is subject to wide variation and modification within the scope of the appended claims without departing from the scope or intent of the present invention.

What is claimed is:

1. A machine for playing bridge and other card games wherein cards are substituted by rolling playing balls, said machine comprising, in combination, means for mixing the playing balls, a separate playing tray at each player's location, a separate sorting tray adjacent each playing tray, whereby said balls may be pushed singly from a playing tray to a sorting tray and may roll back to the playing tray, means selectively transmitting the mixed balls to each playing tray, a playing channel, means transmitting the balls from the playing trays to the playing channel, and means transmitting the balls from said playing channel to said mixing means.

2. A machine for playing bridge and other card games wherein cards are substituted by rolling playing balls, said machine comprising, in combination, a platform, means for mixing the playing balls and for transmitting them to said platform, inclined channels extending between said platform and players' locations, a movable gate situated between said platform and said channels, a separate pin situated within each channel to prevent the balls from reaching the players' locations, means connecting said gate with said pins for raising said pins when said gate is lowered and vice versa, a playing channel, means transmitting the balls from the players'

locations to the playing channel, and means transmitting the balls from said playing channel to said mixing means.

3. A machine for playing bridge and other card games wherein cards are substituted by rolling playing balls, said machine comprising, in combination, means for mixing the playing balls, a separate receiving tray at each player's location, a sorting tray situated close to said receiving tray and adapted to receive balls pushed singly from said receiving tray, a playing channel, means for transmitting the balls from said sorting tray to said playing channel, means interrupting the communication between said sorting tray and said playing channel and transmitting the balls from said sorting tray to said receiving tray after the sorting of the balls is completed, and means transmitting the balls from said playing channel to said mixing means, and means transmitting the balls from said mixing means to said players' locations.

4. A machine for playing bridge and other card games wherein cards are substituted by rolling playing balls, said machine comprising, in combination, means for mixing the playing balls, a separate receiving tray at each player's location, a sorting tray situated parallel and close to said receiving tray and adapted to receive balls pushed singly from said receiving tray, means pivotally supporting said trays at adjacent ends thereof, a playing channel, another channel extending between said playing channel and the pivoted end of said sorting tray, a barrier, means for inserting said barrier between said other channel and said sorting tray and for raising the other end of said sorting tray after said balls have been sorted, and means transmitting the balls from said playing channel to said mixing means, and means transmitting said balls from said mixing means to said receiving tray.

5. A machine for playing bridge and other card games wherein cards are substituted by rolling playing balls, said machine comprising, in combination, means for mixing the playing balls, a separate receiving tray at each player's location, a sorting tray situated parallel and close to said receiving tray and adapted to receive balls pushed singly from said receiving tray, means pivotally supporting said trays at adjacent ends thereof, a playing channel, another channel extending between said playing channel and the pivoted end of said sorting tray, a barrier, means for inserting said barrier between said other channel and the pivoted end of said sorting tray during the sorting and the return of the balls, means for lowering the other end of said sorting tray during the sorting, means for raising said other end of the sorting tray and for lowering the corresponding end of the receiving tray to return the sorted balls from the sorting tray to the receiving tray, and means transmitting the balls from said playing channel to said mixing means, and means transmitting the balls from said mixing means to said receiving tray.

6. A machine for playing bridge and other card games wherein cards are substituted by rolling playing balls, said machine comprising, in combination, means for mixing the playing balls, a separate receiving tray at each player's location, a sorting tray situated parallel and close to said receiving tray and adapted to receive balls pushed singly from said receiving tray, a playing channel, a dummy-hand channel, means for transmitting the balls from said sorting tray to said playing channel, means for transmitting the balls from said

balls from said receiving tray to said dummy-hand channel, and means transmitting the balls from said playing channel to said mixing means, and from said mixing means to said receiving tray.

7. A machine for playing bridge and other card games wherein cards are substituted by rolling playing balls, said machine comprising, in combination, means for mixing the playing balls, a separate receiving tray at each player's location, a sorting tray situated parallel and close to said receiving tray and adapted to receive balls pushed singly from said receiving tray, a playing channel, a dummy-hand channel fitting into said playing channel, means for raising said dummy-hand channel above said playing channel, means for selectively conveying the balls from said receiving tray to said dummy-hand channel and from said sorting tray to said playing channel, and means transmitting the balls from said playing channel to said mixing means, and means transmitting the balls from said mixing means to said receiving tray.

8. A machine for playing bridge and other card games wherein cards are substituted by rolling playing balls, said machine comprising, in combination, a rectangular casing enclosing an inner space, a device connected to said casing for mixing the playing balls, means within said casing

for receiving the mixed balls and selectively transmitting the mixed balls to players' locations, a playing channel situated in said inner space, a dummy-hand channel situated in said inner space and movable in relation to said playing channel, means situated within said casing for transmitting the balls selectively from the players' locations to the playing channel and the dummy-hand channel, and means transmitting the balls from said playing channel to said mixing means.

9. A machine for playing bridge and other card games wherein cards are substituted by rolling playing balls, said machine comprising, in combination, means for mixing said balls and raising them to an elevated position, means for sorting the raised balls into hands or sets, a separate playing tray at each player's location, a separate sorting tray adjacent each playing tray, whereby said balls may be pushed singly from a playing tray to a sorting tray and may roll back to the playing tray, means for delivering said hands of balls to the playing trays, a playing channel, means for transmitting the balls from the playing trays to said playing channel, and means for transmitting the balls from said playing channel to said mixing means.

JOHN J. HICKEY.
